MAN'S UNDERGARMENT

Arthur M. Reis, New York, N. Y., assignor to
 Robert Reis & Co., New York, N. Y., a corpora-
 tion of New York

Original application May 22, 1939, Serial No.
 274,999. Divided and this application March 7,
 1940, Serial No. 322,651

3 Claims. (Cl. 2—234)

The invention relates to men's undergarments and is equally applicable to garments of this general type which are either those known as "shorts," those which embody leg structures of 5 comparatively short lengths, overlying only a portion of the thighs of the wearer, or those having leg structures which extend the full length of the body to the ankles. The present application is a division of my co-pending application, 10 Serial No. 274,999, filed May 22, 1939.

More particularly, the invention relates to a construction of an undergarment in which a front section, usually constituting a gore, is made of two overlying plies of material, which front section, when the garment is worn, overlies the private parts of the body and usually extends to substantially the elastic waistband of the garment.

In structures of this type of undergarment, no conventional form of fly opening is provided, it being necessary to insert the hand at the elongated opening at one side of the gore, so that the hand is disposed between the plies of material, and then to pull aside the back ply to substantially the position of the opening in the side of the gore and thus provide a means of egress for the private part of the body from the garment.

The object of the present invention is to provide a construction of undergarment of this general type, in which an easy means of egress is provided through the material of the garment, eliminating this objectionable feature of the prior structures. In its broadest aspects, the invention resides in providing an elongated aperture in the underlying ply of the duplex gore, the aperture being so placed that it extends from a point of anchorage at an angle to, or across, in a firm edge of the garment material, for instance the tape constituting one side edge of the gore, or the 40 waistband of the garment, constituting the upper edge of the gore. In accordance with the invention, the elongated aperture is circumscribed by elastic stitching, or stitching enclosing an elastic cord, which will impart to the aperture sufficient resiliency, as distinguished from the comparatively small degree of elasticity of the fabric itself, to bring the aperture back to its normal, substantially closed, condition after it has been stretched. In accordance with the embodiments 50 of the invention illustrated in my aforesaid co-pending application, the elastic elongated aperture is anchored to one of the substantially inelastic tapes constituting the sides of the duplex gore, while in the instant case, the anchoring is effected in the waistband of the garment. This

anchoring of the elongated aperture serves to insure the return thereof, after it has been stretched in its function of providing a means of egress from the garment, to its position in which it is substantially closed. 5

In accordance with my invention, therefore, I provide in an undergarment having a duplex or double ply front section, a hidden opening contributing in great measure to the comfort of the wearer of the garment, without evidencing any 10 external indication of the presence of such opening when the garment is on the body.

In the accompanying drawing, I have illustrated a specific embodiment of my invention, in which an elastic opening is applied to the 15 double ply front section of the garment, in a position in which it is anchored at the waistband of the garment and extends therefrom in the general direction of the wales of the fabric constituting such double ply gore. 20

In the drawing, Fig. 1 is a front view of a garment in the construction of which my invention has been embodied, Fig. 2 is a view of the garment turned inside out to illustrate the disposition and anchoring of the elongated aperture in 25 the double ply front section or gore; and Fig. 3 is a section on the line 3—3 of Fig. 1.

Referring more particularly to the drawing, in which similar reference characters identify similar parts in the several views, the garment illustrated comprises a rear or seat section 10 to which at each side are joined, by stitching 11 and 12, front portions 13 and 14, respectively. An elastic waistband 15 extends throughout the upper periphery of the garment. The sections 10, 13 and 30 14 are constituted preferably of knitted material in which the wales extend substantially longitudinally of the garment, thereby imparting to the garment body substantially no vertical resiliency but a transverse resiliency of considerable degree. 35

The garment is provided with leg structures 16 and 17 having trimmings 18 in the nature of selvages running throughout the leg openings. Such selvages are secured to the edges of the leg openings by lines of stitching 19 which may, or 45 may not, include between them an elastic cord.

The central portion or gore section 20 of the garment, extending from the horizontal line of stitching 21 in the crotch portion, to the elastic waistband 15, is constituted of two plies of material 22 and 23, the latter overlying the former, the entire gore being secured on one side by means of the substantially inelastic tape 25 stitched to the front section 13 through part of its length and forming throughout the remainder 50 55

of its length, with the underlying portion of the section 18, an opening extending from the point 28 of securement of the tape 26, to the point 28' of such tape slightly above the horizontal line of 5 stitching 21.

The central gore section tapers, by reason of 10 the provision of the leg structures, downwardly. Extending upwardly from the line of stitching 21 in the crotch portion of the garment, is a "dart" 15 structure generally designated at 27, the function and construction of which is set forth in my Patent No. 2,140,459, December 13, 1938.

The means of egress, constituting the subject 20 matter of the present invention, comprises an elongated, substantially flat and narrow slot or aperture 28 formed in the underlying ply 22 of the gore section, such elongated aperture being formed by stitching 29 enclosing an elastic cord. The stitching and enclosed elastic cord are anchored at the upper extremity of the elongated 25 aperture to the elastic waistband of the garment and extends generally in the direction of the wales of the fabric constituting the gore ply.

The positioning of the elongated aperture and 30 its anchoring to the firm edge of the waistband imparts to the aperture the property or characteristic of ready stretchability and that degree of resiliency which will cause it to resume its original position and condition of being substantially closed when the force stretching it has been relieved. By anchoring the elongated aperture, or rather the material forming the same, to a firm edge, it will always return to its original 35 position by reason of its own elasticity as well as the inherent resiliency of the knitted fabric in which it has been produced.

I claim:

1. A man's undergarment having a front gore 40 constituted of two plies of knitted material and adapted to have a portion thereof overlie the private parts of the body when the garment is worn, the wales of at least the underlying ply of mate-

rial extending longitudinally of the gore, said underlying ply having a means of egress therethrough, constituted of a narrow, elongated aperture circumscribed by elastic stitching and extending from a point of anchorage in a firm edge 5 of the garment material and terminating at a point removed from any other firm edge of such garment material, whereby it will, upon release of tension applied in spreading it, return to its original narrow, elongated and substantially closed condition and extend throughout a portion of the length of said ply in the general direction of the wales thereof.

2. A man's undergarment having an elastic waistband and a front gore constituted of two plies of knitted material and adapted to have a portion thereof overlie the private parts of the body when the garment is worn, the wales of at least the underlying ply of material extending longitudinally of the gore, said underlying ply 15 having a means of egress therethrough, constituted of a narrow, elongated aperture circumscribed by elastic stitching and extending from a point of anchorage at the lower edge of the waistband of the garment throughout a portion 20 of the length of said ply and in a direction substantially parallel to the wales thereof.

3. A man's undergarment having a front gore constituted of two overlying plies of knitted material and adapted to have a portion thereof 30 overlie the private parts of the body when the garment is worn, the underlying ply having a means of egress therethrough, constituted of a narrow, elongated aperture circumscribed by elastic stitching and extending from a point of anchorage in a firm edge of the garment material and terminating at a point removed from any other firm edge of such garment material, whereby it will, upon release of tension applied in spreading it, return to its original narrow, 35 elongated and substantially closed condition.

ARTHUR M. REIS.
